LABELING MACHINE GLUEPOT

Edgar M. Sims, San Jose, Calif.

Application February 20, 1940, Serial No. 319,893

4 Claims. (Cl. 91—50)

The present invention relates particularly to means for placing label pick-up glue on a rolling can.

In the canning industry it is common practice to apply labels to the cans by rolling the cans over a gluepot where dabs of glue are placed thereon, then causing each rolling can to pick up a label by one edge by means of said glue, and finally wrapping the label around the can and sealing the opposite edge of the label over the first one.

The means for applying the glue to the cans in the operation above outlined has heretofore been a very unsatisfactory one, because it does not deposit the proper amount of glue on the can in the correct form to secure the best results. This is partly, but not wholly, due to the fact the commercial can is not perfectly cylindrical, the formation of the seam along the side of the can preventing the formation of a true cylinder. Furthermore, many cans are slightly dented or otherwise deformed so that a fixed glue applying means can not be depended upon to operate perfectly at all times, placing little or no glue in indentations and placing too much glue on elevated surfaces, when such surfaces register with the glue-applying devices.

When a can fails to receive glue through the failure of the glue applying device to properly contact it, it does not, of course, pick up a label and must be removed and sent through the machine again. If insufficient glue is applied the label pick-up is not positive and the result is obvious. If too much glue is applied neither the pick-up nor the positioning of the label is positive. And if too much glue is applied, or if the glue is not applied in the proper form, that is in the proper formation on the can, it will extend beyond the edge of the label to which it is applied with the result that it will be absorbed by the single thickness of the overlying label and disfigure the visible surface of the same.

It is, therefore, one object of the present invention to provide a device of the character indicated that will place the desired arrangement, form, and quantity of glue on a rolling can, regardless of any imperfections that may exist in its surface.

It is also an object of the invention to provide means of the character indicated that will be economical to manufacture, simple in form and construction, that consists of few parts, that will be strong, durable, positive in operation, and highly efficient in its practical application.

In the drawing:

Figure 1 is a plan view of a device embodying my invention, a part being broken away.

Figure 2 is a sectional view on line 2—2 of Figure 1.

Figure 3 is an enlarged sectional view of the glue-applying member and its cooperating parts.

Referring now more particularly to the drawing, I show at 1 a glue receptacle supplied with heated liquid glue through an orifice 2 in its bottom communicating with a supply chamber 3. 10 Glue is maintained at a desired height in receptacle 1 by maintaining a similar height in the stand-pipe 4 connected to the supply chamber by passage 5.

At 6 is shown a shaft journaled in the side 15 walls of the receptacle at 1 and rotated continually through the medium of a pulley and gear drive from a power source not shown.

Since it is common practice to apply three spots of glue to each can, and to arrange these spots in 20 a line paralleling the axis of rotation of the can, I have shown three glue-applying units suitably spaced on shaft 6; but since these units are identical in every respect, one only will be described in detail.

Each unit, then, comprises a lever of the first class 9 fulcrumed on the shaft 6 with its weighted end 10 resting on the bottom of receptacle 1 and its other end projecting angularly upward above the top level of the receptacle into the path of travel of the cans, as indicated at 11. The weight of the end 10 is sufficient to normally position the arm or lever in the position shown, yet permit a free and easy swinging movement thereof when a rolling can bears against the end 11.

At 12 is shown a double gear secured to the shaft 6 to rotate therewith by means of a pin 13. This gear is turned down centrally to form an annular groove as 13, and each side of said groove is formed an annular shoulder 14 concentric with the shaft 6. The toothed portions of the gear are indicated at 15, and they have a diameter greater than the diameter of the shouldered portions 14. The diameter of the gear 12 must be such that its lower portion will 45 always be immersed in the liquid glue in the receptacle.

At 16 is a small double gear journaled in the lever 9 as at 17 with its teeth meshing with the teeth of gear 12. The central portion of member 16 is circular in form and concentric with its trunnions 17, and has a diameter greater than that of the toothed portions, and consequently will rotate between the toothed portion 15 in close proximity to shoulders 14 but not con- 55

tacting the same. This small gear 16 is mounted near the top edge of the lever 9, and is so positioned that a rolling can will first contact the surface 18, this contact being instantly followed by contact with the end 11 of lever 9.

5 The several levers 9 are positioned on shaft 6 by means of spacers as 19, and since the gears are placed within slots as 20 in the levers, they are assembled by threading the spacers, levers 10 and gears on the shaft as it is inserted in the receptacle.

It may now be understood that when a can rolls along the track 21 the body thereof will move on a plane as 22 until it reaches and contacts the surface 18 of gear 16. But this contact is instantly followed by contact with the point 11 of lever 9. The moment the can makes this latter contact it operates to turn the lever on its fulcrum 6, and consequently the contact 20 of the can with surface 18 is immediately broken. In this operation the upper edge of the lever 9 passes through some such position as 9a to the position 9b, in which latter position the can passes completely over the end 11 and the lever 25 is permitted to return to its original position.

Since gear 12 is power actuated it is continually moving through the body of glue in the receptacle 1, and is picking up and carrying glue on its surface throughout its complete revolution. Again, since the gear 12 is in mesh with gear 16 it follows that gear 16 is positively rotated, and since this gear rotates the surface 18 in close proximity of shoulders 14 it acquires 30 a film of glue therefrom. When the can contacts the surface 18 it receives a spot of glue that is just right in quantity and that is not spread over the can.

Although but one specific embodiment of the invention has been illustrated and described, it 40 will be understood that various alterations in the details of construction and mode of assembly and operation may be made without departing from the scope of the invention as indicated in the appended claims.

I claim:

45 1. A device of the character described com-

prising, a liquid glue receptacle, a shaft journaled thereon, an arm journaled on the shaft to swing in a vertical plane, means operative to yieldingly support one end of the arm above the top level of the receptacle and in the path of travel of 5 a can rolling thereover, a roller journaled on the arm in a position to contact the can in advance of the arm, and a glue transfer wheel mounted on the shaft to rotate therewith and constructed and arranged to pick up glue in the receptacle 10 and deposit it on the roller.

2. A device of the character described comprising, a liquid glue receptacle, a driven shaft journaled therein, an arm journaled on the shaft to swing in a vertical plane, means operative to 15 yieldingly support the arm in angular relation to the path of travel of a can passing thereover with the free end of the arm extending above the top level of the receptacle to lie in the path of travel of a can rolling thereover, a glue applying roller 20 journaled on the arm in a position to contact the can in advance of the arm, and a glue transfer wheel mounted on the shaft to rotate therewith and constructed and arranged to pick up glue from the receptacle and deposit it on the roller. 25

3. A device of the character described comprising, a glue receptacle, a driven shaft journaled therein, an overbalanced arm mounted on the shaft to swing in a vertical plane with one end normally disposed in the path of travel of 30 a can rolling thereover, a geared wheel journaled on the arm and disposed to contact the can in advance of the arm end, and a geared wheel mounted on the shaft to rotate therewith and meshing with said first geared wheel whereby to 35 rotate said first geared wheel and convey glue thereto.

4. The structure set forth in claim 3 wherein the geared wheel on the driven shaft has a shoulder formed thereon in concentric relation to its 40 axis, and the geared wheel journaled on the arm has a portion of greater diameter than its toothed portion and disposed to rotate in close proximity to the said shoulder to receive glue therefrom.
